UNITED STATES PATENT OFFICE.

RICHARD MACKIN, OF GROVETON, NEW HAMPSHIRE.

WRENCH.

1,295,546.

Specification of Letters Patent. Patented Feb. 25, 1919.

Application filed July 5, 1918. Serial No. 243,317.

To all whom it may concern:

Be it known that I, RICHARD MACKIN, a citizen of the United States, residing at Groveton, in the county of Coos and State 5 of New Hampshire, have invented new and useful Improvements in Wrenches, of which the following is a specification.

The present invention relates to improvements in the construction of wrenches, one 10 object being to provide a wrench wherein the slidable jaw may be quickly moved toward or away from the stationary jaw, to automatically lock the sliding jaw in its adjusted position, and to further provide 15 means whereby minute adjustment may be obtained to permit of an article being firmly engaged by the jaws, or to permit the sliding jaw to be moved only a slight distance away from the article to allow the wrench 20 to be brought out of engagement with the said article to retain the jaws in position to engage with a similar sized article.

Another object of the invention is to provide a wrench having its slidable jaw 25 formed with a toothed angular member which abuts one of the edges of the shank of the stationary jaw and which is received in a suitable pocket in the handle of the wrench, to arrange upon the said handle or 30 upon the shank of the stationary jaw a sliding plate carrying a rotatable, exteriorly threaded, adjusting nut, and to provide one of the ends of said sliding plate with an arched resilient tail which is secured at its 35 end to the handle and which normally forces the adjusting nut into engagement with the toothed member of the movable jaw; said arched resilient member, when contacted, being adapted to move the plate in one direction 40 so as to move the threaded adjusting nut or screw out of engagement with the angular threaded member of the movable jaw to permit of the free and quick adjustment of the movable jaw toward or away 45 from the stationary jaw.

A still further object of the invention is to simplify and improve the existing art by producing a wrench which is simple in construction, easily and quickly adjusted, 50 cheap to manufacture and which will perform the functions for which it is devised with accuracy and with surety.

With the above and other objects in view, the improvement resides in the construction, 55 combination, and arrangement of parts set

forth in the following specification and falling within the scope of the appended claims.

In the drawing:

Figure 1 is a side elevation of a wrench constructed in accordance with the present 60 invention.

Fig. 2 is a transverse sectional view approximately on the line 2—2 of Fig. 1. Fig. 3 is a horizontal sectional view approximately on the line 3—3 of Fig. 2. Fig. 4 is 65 a sectional view approximately on the line 4—4 of Fig. 1, but illustrating the slidable plate arranged in guideways in the handle, and Fig. 5 is a perspective view of the slidable plate and the resilient tail formed 70 therewith.

In the drawing of the wrench the numeral 1 includes a stationary jaw 2 having an angular shank 3 to which is secured a handle 4, while mounted, for slidable movement, 75 upon the shank 3 is the movable jaw 5.

The movable jaw is formed, or otherwise provided, with a right angular extension 6 which rests snugly against one of the edges of the shank 3 and which has its free end 80 received in a suitable depression or pocket 7 provided in the handle 4. The outer face of the extension 6 is concaved and is provided with teeth, indicated by the numeral 8 and as seen in Fig. 2 of the drawings. 85

The numeral 9 designates a sliding plate which is provided with an opening 10 corresponding in shape and area with the cross sectional diameter of the shank 3 and the extension 6 of the jaw 5. The opening 10 is 90 of a sufficient length to permit of the plate 9 being moved any desired distance over the shank 3 of the extension 6 for a purpose which will presently be described. The plate 9 may rest upon the flat inner end of the 95 handle 4, or the same may be provided with guides 11 which are received in guideways 12 in the said handle 4, as illustrated in Fig. 4 of the drawing. The end wall, provided by the slot or opening 10 disposed adjacent 100 the concaved threaded edge or face of the extension 6, is preferably arched or of a convex formation, to be snugly received within the said concaved surface of the extension 6, and said plate, beyond the arched or rounded edge, indicated for distinction by the numeral 13, is provided with a removable pin 14 which provides a shaft or trunnion for

105 an adjusting worm or screw 15. The opposite end of the plate 9 is integrally formed 110

with an outwardly curved or arched tail piece 16, and the end of the said tail is secured, as at 17 to the edge of the handle 4, as clearly illustrated in the drawing.

5 The operation of the device may be briefly described as follows: When the jaw 5 is to be slid toward or away from the jaw 2, to obtain a quick adjustment between the said jaws, a pressure by the finger or thumb of 10 the operator upon the arched shaped tail 16 causing the plate 9 to slide transversely of the shank 3 or the handle 4 and thus move the adjusting screw 15 out of engagement with the threads 8 upon the concaved face 15 of the angular extension 6 of the jaw 5.

When the jaws are properly adjusted, the pressure upon the said tail 16 is released, and the tail, through its resiliency, will again slide the plate 9 to its initial position 20 and so bring the threads of the adjusting screws 15 into engagement with the threads 8 of the member's 6. The threads of the adjusting screw 15 are milled so that the said screw may be readily revolved upon its shaft 25 14 to permit of a minute adjustment being obtained between the jaws 2 and 5 as well as to permit of the jaw 5 being only a short distance from an object engaged between the said jaws so as to arrange the jaws in position 30 to engage with another object of a similar size.

From the above description, taken in connection with the accompanying drawing, the simplicity of the device, as well as the advantages thereof will, it is thought, be perfectly apparent to those skilled in the art to which such invention appertains without further detailed description.

Copies of this patent may be obtained for five cents each, by addressing the "Commissioner of Patents, Washington, D. C."

Having thus described the invention, I claim:—

1. In a wrench, in combination, a stationary jaw having a shank, a handle secured to the shank, and a movable jaw slidable upon the shank, of an angularly extending member for the movable jaw, said member 40 contacting with one of the edges of the shank and received in the handle, said member having its outer face threaded, a slidable plate straddling the shank and the extension of the movable jaw, an adjusting screw upon the plate, and said plate having an arch-shaped resilient tail piece secured to the handle adapted to normally force the threads of the adjusting screw in coacting engagement with the threads of the movable jaw extension. 45

2. In a wrench, in combination, a stationary jaw having a shank, a handle for the shank and a movable jaw upon the shank, of an angular extension for the movable jaw 60 contacting with one of the edges of the shank and received in the handle, said angular extension having its outer face concaved and threaded, a slidable plate supported by the handle and straddling the shank and the 65 last mentioned member, an adjusting screw journaled upon the plate, a resilient tail piece formed with the plate, a resilient tail piece being arched and having its end secured to the handle and normally sliding the plate in one direction to bring the threads of the 70 adjusting screw into engagement with the threads of the extension of the movable jaw.

RICHARD MACKIN.
